SCREW-ROLLING MACHINE.

Application filed February 27, 1926, Serial No. 91,133, and in Austria January 18, 1926.

This invention relates to screw rolling machines in which the thread is rolled into the shank by two rolling dies having cut into their adjacent sides the grooves required for producing the thread. The two rolling dies are reciprocated at equal speed, but in opposite directions. The shank of the screw brought into position between the two rolling dies is thus rotated by these 5 dies around its geometrical axis. In these machines it is necessary to compensate for the displacement of the shank metal due to the rolling which displacement would otherwise result in an increase of the outer 10 diameter of the threaded part of the bolt beyond the diameter of the shank body. For this purpose a chip is cut off the thread while this is being rolled and in most cases the screw is pointed at the same time and 15 in many cases also the underside of the screw head is turned down to the desired shape.

For this purpose chipping and pointing knives are provided which during rolling 20 are moved radially and axially respectively relatively to the geometrical axis of the bolt or screw according to the gradual increase of the outer diameter of the thread.

The required movement is imparted to 25 the chipping knives arranged diametrically opposite each other relatively to the geometrical axis of the bolt or screw and if desired also to the pointing knife by securing these knives to carriers or slides 30 which are moved at all times with equal speeds but in opposite directions so that these knives approach or recede from the geometrical axis of the bolt simultaneously 35 by equal distances. These movements of the 40 knife carriers are derived from one of the rolling dies.

Now in order to prevent the rolling dies from coming into contact with the knives which would be detrimental to the rolling 45 dies as well as to the knives and would give rise to frequent interruptions of operation, according to the present invention, guiding ribs for the knives are rigidly secured to the rolling dies which ribs enclose between them the knives and reliably prevent any lateral distortion or vibration of the knives 50 which might result from the lateral strains exerted by the blank during the cutting.

In the drawings Fig. 1 is a longitudinal section and

Fig. 2 a transverse section on the line II—II Fig. 1 of a constructional form of the present invention in a screw rolling machine.

Fig. 3 is a plan view of a part of the 60 machine and Figs. 4 and 5 show a modification of the arrangement of the guiding ribs on the rolling dies.

In the constructional form shown by way of example it is assumed that the rolling dies 65 1, 2 are nicely adjustably mounted in supports 3, 4 and are reciprocated for instance by racks and pinions in guides of the machine frame in such a manner that they have at every moment equal but opposite 70 speeds. The stroke of the rolling dies is so selected that at each end of the stroke the one has fully passed the other. The bolt blanks are brought into position between the rolling dies before the beginning 75 of the working stroke so that the blank apart from a slight axial movement due to the pitch of the thread has imparted to it only a rotary movement around its geometrical axis.

In a casing 5 fixed on the machine frame two knife carriers 6, 7 are adjustably secured to slides 8, 9 movable parallel to the direction of movement of the rolling dies. To the knife carriers the chipping knives 85 10, 11 are secured, the chipping edges 16, 17 of which are diametrically opposite each other relatively to the geometrical axis of the blank. The slides 8, 9 are mechanically connected with each other in such a manner that they always move through equal distances, but in opposite directions. This mechanical connection comprises for instance a pinion 14 and two racks 12, 13. A rocking movement is imparted to the 90 pinion 14 in accordance with the reciprocating movement of the knives. This rocking movement is derived from one of the rolling die slides, say 31. For instance a lever 19 journaled in the casing 5 one of the ends of the lever provided with a roller running along a cam 20 secured to the slide 31 and the other end of the lever carries a toothed sector engaging into a pinion 21 100 on the shaft of the pinion 14.

While during the working stroke of the

- rolling dies the thread is rolled into the blank the part of the cam 20 having a slight inclination moves along below the end of the lever 19 engaging with it and both slides 8, 9 are moved simultaneously from opposite sides towards the blank, rotating around its geometrical axis, through the medium of the lever 19, the toothed sector, the toothed wheels 21 and 14 and the racks 12, 13 for cutting off uniformly a chip from the outer periphery of the thread being formed on opposite sides thereof, so that finally the finished thread has the same outer diameter as the shank of the bolt.
- 15 When the thread is finished the rolling dies still continue their movements, the end of the lever 19 provided with the roller running over the part of the cam inclined at a greater angle and the slides 8, 9 are forced apart by springs 32 interposed between them and the frame 5; thus the knives come out of engagement with the finished bolt or screw and the latter is released and drops from the machine. Then the rolling dies begin the idle return stroke and the slides 8, 9 with the knives 10, 11 are moved towards each other so that at the end of the return stroke a fresh blank may be inserted between them. This is secured by the slightly inclined part 30 of cam 20 at the other end of the same.
- If it is desired to point the screw simultaneously with taking off the chip either a separate pointing knife may be used or a pointing edge 18 may be provided on one of the chipping knives say 10. In any case the pointing edge must make during the rolling of the thread a movement parallel to the geometrical axis of the blank and the stroke of this movement must correspond to the axial movement of the blank in the course of the rolling of the thread. This movement of the edge 18 is derived from one of the rolling die slides, preferably from the slide 31 or the support 3, a cam 22 being secured 40 to the same on which runs against the action of a suitable spring 33 a roller on a knife carrier guided parallel to the axis of the blank in the frame of the machine or in the casing 5.
- 50 In order to prevent the knives from being laterally distorted or vibrated by the rapid movement of the rolling dies and more particularly by the lateral strains exerted upon them by the blank owing to the cutting off of the chip whereby the knives might come into contact with the rolling dies which would be detrimental to both knives and the rolling dies and would lead to frequent interruptions of operation, guiding ribs 41, 42 are rigidly connected to the rolling dies which ribs guide the knives laterally and thus prevent any lateral distortion or vibration of the same. These guiding ribs may be constructed as shown in Figs. 1 and 2 as washer plates adjustably and rigidly secured
- in the rolling die slides, or these washer plates may be mounted on the rolling dies themselves and fixed in position by any suitable means, as shown in Figs. 4 and 5, if the rolling dies are too broad for the screws 70 to be rolled.
- It is preferable to mount the pointing edge 18 on one of the chipping knives say 10. The carrier 7 of this knife must then make besides the movement radial to the geometrical axis of the blank required for cutting off the chips also a movement parallel to this axis. This can be effected by securing the knife carrier not directly to its slide 9, but to a transverse slide 23 which is guided 75 parallel to the axis of the blank and secured to the slide 8. The transverse slide then carries the roller running on the cam 22 and is acted upon by the spring 33.
- As the rolling dies begin their working 85 stroke the pointing knife or edge 18 of the knife carrier 7 is moved towards the end of the blank and turns the same down in the course of the working stroke. At the end of the working stroke the chipping knives 90 recede from each other and the pointing edge 18 is moved away from the blank simultaneously so that the latter is released and may drop freely out of the machine. During the idle return stroke of the rolling dies 95 the pointing knife is returned into its initial position.
- For easily and readily exchanging the knife carriers and for nicely adjusting the knives, the knife carrier is adjustably secured to the associated slide 8, 9 or to the slide 8 and the transverse slide 23 by means of clamping screws and elongated holes and furthermore the knife carriers are held between adjusting screws 25 on the slides 8, 9 100 or on the slide 8 and the transverse slide 23. It is sufficient to loosen a few readily accessible screws for releasing the knife carriers and removing them from the slides whereupon they can be replaced by others and also 105 the knife carriers 6, 7 may be adjusted without difficulty.
- The exchange of the cams 20, 23 for varying the thickness of the chip and the pointing 110 is just as simple because also these parts are screwed to the slide 31 or support 3 and are readily accessible.
- The entire arrangement is very simple, compact cheap and reliable in operation and permits to easily and rapidly remove the parts for sharpening or exchange because the casing 5 is fixed in the frame and open on the front side and also permits a very 115 simple and exact adjustment. Finally the arrangement is very durable because the movements which the knife carriers have to make are only small and slow.
- What I claim is:—
1. In a screw rolling machine the combination of rolling dies adapted to revolve a

- screw blank interposed between them around its geometrical axis, means adapted to move said dies simultaneously in opposite directions with equal speeds, two chipping knives 20 arranged diametrically opposite each other with relation to the geometrical axis of the said blank, slides one for each knife controlled by the rolling dies for moving such slides simultaneously in opposite directions 25 with equal speeds and washers, rigidly connected to the said rolling dies and projecting beyond such rolling dies towards the said knives whereby the latter are laterally guided between the rolling dies. 30
- 5 2. In a screw rolling machine the combination of rolling dies adapted to revolve a screw blank interposed between them around
- 10
- 15

In testimony whereof I have affixed my signature.

JULIUS HELLER.
